UNITED STATES PATENT OFFICE

2,427,759

CYLINDER COOLING MEANS

Jeri Zuljivech, Fresno, Calif.

Application July 29, 1944, Serial No. 547,270

3 Claims. (Cl. 123—173)

1

My invention relates to improvements in means for cooling the cylinders of internal combustion engines.

The primary object of my invention is to facilitate the transfer of heat from the cylinders of internal combustion engines of the liquid cooled type, while at the same time decreasing the weight of the cylinders, strengthening the same and reducing to a minimum obstruction of the flow of the cooling medium, all without materially increasing manufacturing or replacement costs.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in vertical section of a cylinder equipped according to my invention, in the preferred embodiment thereof,

Figure 2 is a fragmentary view in transverse section taken on the line 2—2 of Figure 1,

Figure 3 is a view in horizontal section taken on the line 3—3 of Figure 1 and drawn to an enlarged scale,

Figure 4 is a view in horizontal section of a modified embodiment of my invention, and

Figure 5 is a view in vertical section of another modified embodiment.

Referring to the drawings by numerals, and first to Figures 1 to 3, according to my invention, in the preferred embodiment thereof, a steel cylinder 1 of an internal combustion engine, of the water cooled type, and including the usual liquid cooling jacket 2, base attaching flange 3, and hollow head 4 is provided with vertical, circumferentially spaced fins 5 tapering in cross section from the cylinder and formed integrally with the cylinder wall proper. The fins 5 are preferably spaced at the lower ends thereof from the bottom of the cooling jacket 2, extend to the bottom of the head 4, and are spaced from the inner wall of said jacket.

The fins 5 are capped by a sleeve-like casing 6 of metal having a higher coefficient of conductivity as regards the transfer of heat than the fins 5, said casing having hollow fins 7 of the same shape as the fins 5 fitting over said fins 5 and likewise spaced from the inner wall of the liquid cooling jacket 2. The casing 6 is preferably formed of aluminum and is shrunk on the fins 5 into intimate flush engagement therewith throughout the length of the same.

The cylinder head 4, as shown, comprises a main spider plate 8 for closing the upper end of the cylinder 1, having the usual raised center 9 provided with the socket 10 for receiving the

2

spark plug 11, and a well 12 around said plug, a ring section 13 forming an extension of the liquid cooling jacket 2 connected to said spider 8 by integral, circumferentially spaced, radial apertured ears 14, and an upper, annular cap plate 15 provided with internal circumferentially spaced lugs 16. Bolts 17 extending through the cap plate 15, lugs 16 and ears 14 and also through internal lugs 18 in the upper end of the liquid cooling jacket 2, secure the described head parts together and to said jacket 2. The spider 8 of the head 4 is provided with parallel fins 19, similar to fins 5, extending across the top thereof and formed integrally therewith and, preferably, when the head is not of the aluminum type, said fins 5 are capped by an annulus of hollow fins 20 similar to the fins 7 fitting around the center 9 and shrunk on said fins 19.

In the modified embodiment of my invention shown in Figure 4, a tubular sleeve 21 having longitudinally extending solid fins 22 formed therewith, and which is of the same material as the casing 6, with the fins 22 similar to the fins 7, is provided on the cylinder 23 within the liquid cooling jacket 24, said fins 23, as shown, being solid.

As shown in Figure 5, the cylinder 25 of an airplane liquid cooled engine may be provided with longitudinal fins 26 similar to fins 22 and preferably integral with the cylinder 25. The head 27 may be provided with circular internal fins 28 around the intake and exhaust valves 29, 30 and with internal fins 31 between said valves, all cast with the head.

As will now be seen, my invention comprises providing the cylinders of internal combustion liquid cooled engines with a maximum heat transfer surface of ribbed form in which the ribs are arranged to extend in the direction of the flow of the cooling medium, thereby obviating, as far as possible, resistance to flow of the cooling medium. The cooling surface is provided on the cylinder wall proper, where the greatest heat is generated, as distinguished from the cooling jacket, thereby facilitating cooling the engine, as will be clear. Since the fins strengthen the same, the walls of the cylinder, and also the head, may be cast lighter than can now be accomplished, without sacrificing strength. With cast steel cylinders and head, and even with aluminum heads, my improved arrangement of cooling means will effect transfer of a greater amount of heat than has heretofore been possible and such transfer will be accelerated as compared with the rate of transfer in present day engines.

The foregoing will, it is believed, suffice to impart a clear understanding of my invention without further explanation.

Manifestly, the invention, as described, is susceptible of modification without departing from

the inventive concept, and right is herein reserved to such modifications as fall within the scope of the appended claims.

What I claim is:

1. The combination with an internal combustion engine cylinder, and a jacket surrounding the cylinder for containing a cooling liquid, of cooling fins radiating from the cylinder in circumferentially spaced-apart relation and extending lengthwise of said cylinder with outer edges spaced from said jacket, said cylinder having a hollow head closing the same and forming a part of said jacket and provided with internal horizontal fins.

2. The combination with an internal combustion engine cylinder, and a jacket surrounding the cylinder for containing a cooling liquid, of cooling fins radiating from the cylinder in circumferentially spaced-apart relation and extending lengthwise of said cylinder with outer edges spaced from said jacket, said cylinder having a hollow head forming a part of said jacket and provided with internal horizontal fins, said fins tapering in cross section outwardly.

3. The combination with an internal combustion engine cylinder, and a jacket surrounding the cylinder for containing a cooling liquid, of

10
5

cooling fins radiating from the cylinder in circumferentially spaced-apart relation and extending lengthwise of said cylinder with outer edges spaced from said jacket, and a casing comprising hollow fins fitting around said cylinder and over said cooling fins and formed of a metal having a higher coefficient of conductivity in the transfer of heat than the fins first mentioned.

JERI ZULJIVECH.
